LUMINAIRE

Edwin F. Guth, Jr., Ladue, Mo., assignor to The Edwin F. Guth Company, St. Louis, Mo., a corporation of Missouri

Application August 28, 1958, Serial No. 52,437

Term of patent 14 years

(Cl. D48—23)

FIG.1

The border which projects from the sides of the article is shaded to show contrast.

I claim:

The ornamental design for a luminaire, as shown and described.
